(57) **CLAIM**

The ornamental design for a storage container, as shown and described.

DESCRIPTION

FIG. 1 is a front, perspective view of a storage container in an assembled and closed configuration with a plunger inserted; FIG. 2 is a front elevational view of the storage container thereof, the rear, left and right elevational views of the design being the same;

FIG. 3 is a top view of the storage container of FIG. 1; FIG. 4 is a bottom view of the storage container of FIG. 1; and, FIG. 5 is a cross sectional view of the storage container thereof, taken along line 5-5 of FIG. 3.

The broken lines shown are included for the purpose of illustrating portions of the stand that form no part of the claimed design.

1 Claim, 4 Drawing Sheets
